(57) **CLAIM**

The ornamental design for port replicator, as shown and described.

DESCRIPTION

FIG. 1 is a front perspective view of a port replicator in accordance with our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a reference perspective view showing the port replicator before connecting to a laptop computer; and,

FIG. 9 is another reference perspective view showing the port replicator when connecting to a laptop computer.

The broken lines showing a laptop computer in FIGS. 8 and 9 are for illustrative purposes only and form no part of the claimed design.
